LAZY SUSAN

Howard Thompson, Minneapolis, Minn.

Application September 30, 1955, Serial No. 537,656

10 Claims. (Cl. 211—85)

This invention relates to improvements in rotatable multi-compartment dispensing devices and is concerned, more particularly, with devices of the character known as Lazy Susans.

Among the disadvantages of present Lazy Susans are that they are bulky and require excessive storage and shipping space. Further, it is well known that they are awkward to handle and usually require two hands for carrying.

It is, accordingly, a principal object of the present invention to provide a Lazy Susan or similar device which is free of the foregoing and other disadvantages which characterize present devices and which requires only minimum space for storage in the home or in restaurants and which is easily manipulated by the user.

A more specific object is to provide a rotatable multi-compartment dispensing device such as a Lazy Susan which is collapsible and has a plurality of hinged peripheral compartments or bowl supports which may be folded inwardly and stacked within the confines of the central supporting member in very compact position for storage or shipping and wherein only as many compartments or bowl supports as are needed for immediate use need be extended in supporting position.

Another object is to provide a device having pedestal legs which are adapted to be collapsed or folded against the bottom of the central supporting member for still further compactness when not in use and the invention also contemplates the provision of a device having an upright handle for convenience for carrying but which handle may be folded in the plane of the central supporting member when the device is not in use.

In a preferred embodiment of the invention, as hereinafter illustrated and described, the device may be in the form of a rack for supporting a plurality of removable bowls or the like which are readily removed for refilling or cleaning and which may be utilized in any particular number desired.

Other and further objects and advantages of the invention will be apparent from the following detailed description taken in conjunction with the accompanying drawings wherein a preferred embodiment of the principles of the invention has been selected for exemplification.

In the drawings:

Fig. 1 is a top plan view of a device constructed in accordance with the invention in fully extended operative position;

Fig. 2 is a side elevational view of the device shown in Fig. 1;

Fig. 3 is a view similar to Fig. 1 but showing the device in fully folded or storage position;

Fig. 4 is a side elevational view of the device as shown in Fig. 3;

Fig. 5 is an enlarged fragmentary sectional view taken on the line 5—5 of Fig. 3;

Fig. 6 is an enlarged fragmentary side elevational view looking at the handle connection as shown in Fig. 3 and

2

illustrating in solid lines a portion of the handle in folded position and in broken lines in upright operative position;

Fig. 7 is a sectional view taken on the line 7—7 of Fig. 6;

Fig. 8 is an enlarged fragmentary side elevational view showing the hinged connection of one of the supporting pedestal legs;

Fig. 9 is a sectional view taken on the line 9—9 of Fig. 8; and

Fig. 10 is an enlarged view partly in section taken on the line 10—10 of Fig. 3 showing one of the collapsible ring supports in outwardly extended operative position in solid lines and in intermediate and folded positions in broken lines.

Referring more particularly to the drawings, wherein like numerals refer to like parts, the device as illustrated comprises a central supporting dish-like member 10 in the form of a plurality of radially extending arcuate ribs 12 and which is provided with a central platform 14 and an upstanding peripheral rim 16. A folding U-shape spring handle 18 is provided for the device and to facilitate retention of the handle in upright operative position, a rib and groove cam arrangement such as shown at 20 and 22 in Figs. 6 and 7 is preferably provided adjacent the pivotal connections of the opposed ends of the handle 18 with the central supporting member 10. To lock the handle in upright operative position, the pivotal connections may be in the form of a key 21 projecting outwardly of the rim 16 in engagement with an apertured handle end portion 23 which, as shown in Fig. 6, comprises an enlarged part in which the key 21 may be relatively rotated and a narrow part in which the key 21 may be slidably fixed to prevent relative transverse movement of the handle.

It will be apparent that the central platform 14 provides a support for a relatively large or main central serving bowl. For auxiliary bowl supports, a plurality of rings 24 may be carried substantially equidistantly around the periphery of the central supporting member 10 and, for hingedly securing such rings 24, a plurality of angular hinge members 26 are provided one for each of the rings. Each hinge member 26 includes a laterally extending arm 28 to which a ring is attached, integrally or otherwise, and an upright body member 30 having an elongated interior slot 32 in which a portion of the rim 16 is received whereby hingedly to connect each of the rings 24 to the central supporting member 10. It will be apparent, particularly from Figs. 3, 4 and 10, that the elongated slots 32 of the hinge members 26 are relatively slidable with respect to the supporting rim portion 16 so that the rings 24 are adapted to be folded in stacked horizontal position at successive heights within the confines of the central supporting member 10 beneath the plane of the rim 16. The central bowl and the various auxiliary bowls, not shown, may also be nested and stored in the central supporting member 10, if desired.

It will be further apparent, particularly from Figs. 1, 2 and 10, that all or selected rings 24 may be swung outwardly of the central supporting member 10 substantially in the plane of the rim 16 in operative bowl supporting position when desired. The peripheral side wall portion of the central member 10, as shown, is cut away at the portions thereof in the folding path of the hinge members 26 but provision is made for suitable abutment between the hinge body members 26 and a wall portion of the central supporting member 10 for limiting the outward swinging of the ring members 24 and for maintaining the ring members in substantially horizontal position.

A pedestal base, indicated in its entirety at 34, is preferably provided and, as shown, may include a base

plate 36 for rotatably supporting the central member 10 and a plurality of depending pedestal legs 38. The legs 38 are preferably pivotally attached to the base plate 36 for folding upwardly against the base plate for compact storage purposes when the device is not in use. A 5 very convenient construction for this purpose as shown in Figs. 8 and 9 comprises a reversely bent U-shaped spring 40, one for each of the legs 38, carried at the underside of the plate 36 adjacent the pivotal connection 42 of the legs. The bearing arm 44 of each of the 10 springs is provided with a recess 46 for receiving a lug 48 which projects upwardly from each of the legs 38 whereby to lock the legs in extended support position. To release the legs 38 for folding, it is merely necessary to press the spring bearing arm 44 upwardly in the direction of the left hand arrow in Fig. 9 into the broken line position shown so that the lug 48 is clear of the recess 46 and the legs may then be turned upon their pivotal connections 42 upwardly in lateral folded inoperative position.

It is to be understood that the principles of the present invention are not confined to the particular construction and arrangement of parts herein illustrated and described but embrace all such modifications thereof as come within the scope of the following claims.

I claim:

1. A rotatable and collapsible support for a plurality of bowls or the like which comprises, a dish-like central supporting member having an upstanding central platform and an upstanding peripheral rim, a folding U-shaped handle for said support and pivotal connections between the ends of said handle and said support, the said pivotal connections including cam means tending to retain said handle in upright position and means carried by said rim for locking said handle in upright elevated position, a plurality of rings carried substantially equidistantly of said rim and forming auxiliary supporting members, a plurality of angular hinge members one for each of said rings, each of said hinge members including a laterally extending arm for carrying a ring and an upright elongated slotted body member receiving a portion of said rim for hingedly connecting said rings to said central supporting member, the said slotted members being slidable relative to said rim whereby said rings are adapted to be folded in stacked position within said central supporting member beneath the plane of said rim or swung outwardly of said central supporting member in extended article supporting position substantially in the plane of said rim, the said hinge body members being supported in abutting relationship to said central supporting member for limiting the outward swinging of said rings, a base including a base plate rotatably supporting said central supporting member, the said base also including folding pedestal legs pivotally attached to said base plate, springs having recesses carried by said base plate adjacent the pivotal connection of said legs and projecting lugs provided on said legs for engagement with said recesses whereby to lock said legs in extended support position.

2. A rotatable and collapsible support for a plurality of bowls or the like which comprises, a dish-like central supporting member having an upstanding peripheral rim, a folding U-shaped handle for said support and pivotal connections between the ends of said handle and said support, the said pivotal connections including means tending normally to retain said handle in upright position, a plurality of auxiliary supporting members carried substantially equidistantly of said rim, a plurality of angular hinge members one for each of said auxiliary members, each of said hinge members including a laterally extending arm for carrying an auxiliary member and an upright elongated slotted body member receiving a portion of said rim for hingedly connecting said auxiliary members to said central supporting member, the said slotted members being slidable relative to said rim where-

by said auxiliary members are adapted to be folded in stacked position within said central supporting member beneath the plane of said rim or swung outwardly of said central supporting member in extended article supporting position substantially in the plane of said rim, the said hinge body members being supported in abutting relationship to said central supporting member for limiting the outward swinging of said rings, a base including a base plate rotatably supporting said central supporting member, the said base also including folding legs pivotally attached to said base plate, springs having recesses carried by said base plate adjacent the pivotal connection of said legs and projecting lugs provided on said legs for engagement with said recesses whereby to lock said legs in extended support position.

3. A rotatable and collapsible support for a plurality of bowls or the like which comprises, a dish-like central supporting member having an upstanding central platform and an upstanding peripheral rim, a plurality of rings carried substantially equidistantly of said rim and forming auxiliary supporting members, a plurality of angular hinge members one for each of said rings, each of said hinge members including an upright elongated slotted body member receiving a portion of said rim for hingedly connecting said rings to said central supporting member, the said slotted members being slidable relative to said rim whereby said rings are adapted to be folded in stacked position within said central supporting member beneath the plane of said rim or swung outwardly of said central supporting member in extended article supporting position substantially in the plane of said rim, and said hinge body members being supported in abutting relationship to said central supporting member for limiting the outward swinging of said rings, a base including a base plate rotatably supporting said central supporting member, the said base also including folding pedestal legs pivotally attached to said base plate, springs having recesses carried by said base plate adjacent the pivotal connection of said legs and projecting lugs provided on said legs for engagement with said recesses whereby to lock said legs in extended support position.

4. A rotatable and collapsible support for a plurality of bowls or the like which comprises, a dish-like central supporting member having an upstanding peripheral rim, a plurality of auxiliary supporting members carried substantially equidistantly of said rim, a plurality of angular hinge members one for each of said auxiliary members, each of said hinge members including an upright elongated slotted body member receiving a portion of said rim for hingedly connecting said auxiliary members to said central supporting members, the said slotted members being slidable relative to said rim whereby said auxiliary members are adapted to be folded in stacked position within said central supporting member beneath the plane of said rim or swung outwardly of said central supporting member in extended article supporting position substantially in the plane of said rim, the said hinge body members being supported in abutting relationship to said central supporting member for limiting the outward swinging of said rings, a base including a base plate rotatably supporting said central supporting member, the said base also including folding legs pivotally attached to said base plate, springs having recesses carried by said base plate adjacent the pivotal connection of said legs and projecting lugs provided on said legs for engagement with said recesses whereby to lock said legs in extended support position.

5. A rotatable and collapsible support for a plurality of bowls or the like which comprises, a dish-like central supporting member having an upstanding central platform and an upstanding peripheral rim, a folding U-shaped handle for said support and pivotal connections between the ends of said handle and said support, the said pivotal connections including cam means tending to retain said handle in upright position and means carried

by said rim for locking said handle in upright elevated position, a plurality of rings carried substantially equidistantly of said rim and forming auxiliary supporting members, a plurality of angular hinge members one for each of said rings, each of said hinge members including a laterally extending arm for carrying a ring and an upright elongated slotted body member receiving a portion of said rim for hingedly connecting said rings to said central supporting member, the said slotted members being slidable relative to said rim whereby said rings are adapted to be folded in stacked position within said central supporting member beneath the plane of said rim or swung outwardly of said central supporting member in extended article supporting position substantially in the plane of said rim and the said hinge body members being supported in abutting relationship to said central supporting member for limiting the outward swinging of said rings.

6. A rotatable and collapsible support for a plurality of bowls or the like which comprises, a dish-like central supporting member having an upstanding peripheral rim, a folding U-shaped handle for said support and pivotal connections between the ends of said handle and said support, the said pivotal connections including means normally tending to retain said handle in upright position, a plurality of auxiliary supporting members carried substantially equidistantly of said rim, a plurality of angular hinge members one for each of said auxiliary members, each of said hinge members including a laterally extending arm for carrying an auxiliary member and an upright elongated slotted body member receiving a portion of said rim for hingedly connecting said auxiliary members to said central supporting member, the said slotted members being slidable relative to said rim whereby said auxiliary members are adapted to be folded in stacked position within said central supporting member beneath the plane of said rim or swung outwardly of said central supporting member in extended article supporting position substantially in the plane of said rim and the said hinge body members being supported in abutting relationship to said central supporting member for limiting the outward swinging of said rings.

7. A rotatable and collapsible support for a plurality of bowls or the like which comprises, a dish-like central supporting member having an upstanding central platform and an upstanding peripheral rim, a plurality of rings carried substantially equidistantly of said rim and forming auxiliary supporting members, a plurality of angular hinge members one for each of said rings, each of said hinge members including an upright elongated slotted body member receiving a portion of said rim for hingedly connecting said rings to said central supporting member, the said slotted members being slidable relative to said rim whereby said rings are adapted to be folded in stacked position within said central supporting member beneath the plane of said rim or swung outwardly of said central supporting member in extended article supporting position substantially in the plane of said rim and the said hinge body members being supported in abutting relationship to said central supporting member for limiting the outward swinging of said rings.

8. A rotatable and collapsible support for a plurality of bowls or the like which comprises, a dish-like central supporting member having an upstanding peripheral rim, a

plurality of auxiliary supporting members carried substantially equidistantly of said rim, a plurality of angular hinge members one for each of said auxiliary members, each of said hinge members including an upright elongated slotted body member receiving a portion of said rim for hingedly connecting said auxiliary members to said central supporting members, the said slotted members being slidable relative to said rim whereby said auxiliary members are adapted to be folded in stacked position within said central supporting member beneath the plane of said rim or swung outwardly of said central supporting member in extended article supporting position substantially in the plane of said rim and the said hinge body members being supported in abutting relationship to said central supporting member for limiting the outward swinging of said rings.

9. A rotatable and collapsible support for a plurality of bowls or the like which comprises, a central supporting member having an upstanding central bowl supporting platform and an upstanding peripheral rim, a plurality of rings carried substantially equidistantly of said rim and forming auxiliary bowl supporting members, means hingedly connecting said rings to said central supporting member whereby said rings are adapted to be folded in stacked position within said central supporting member beneath the plane of said rim or swung outwardly of said central supporting member in extended article supporting position substantially in the plane of said rim, the said hinge body members being supported in abutting relationship to said central supporting member for limiting the outward swinging of said rings, a base including a base plate rotatably supporting said central supporting member and folding legs pivotally attached to said base plate.

10. A rotatable and collapsible support for a plurality of bowls or the like which comprises, a central supporting member having an upstanding central bowl supporting platform and an upstanding peripheral rim, a plurality of rings carried substantially equidistantly of said rim and forming auxiliary bowl supporting members, means hingedly connecting said rings to said central supporting member whereby said rings are adapted to be folded in stacked position within said central supporting member beneath the plane of said rim or swung outwardly of said central supporting member in extended article supporting position substantially in the plane of said rim and the said hinge body members being supported in abutting relationship to said central supporting member for limiting the outward swinging of said rings.
